UNITED STATES PATENT OFFICE.

LAURENCE E. TOPHAM, OF SWAMPSCOTT, MASSACHUSETTS, ASSIGNOR TO UNITED SHOE MACHINERY CORPORATION, OF PATERSON, NEW JERSEY, A CORPORATION OF NEW JERSEY.

SHOE-SEWING MACHINE.

Application filed December 17, 1917, Serial No. 207,506. Renewed January 26, 1925.

The invention relates to shoe sewing machines, and more particularly to machines of this class in which the shoe is supported on a jack and relative movements are automatically imparted to the stitch-forming mechanism and jack to maintain the shoe in the proper position relative to the stitch-forming mechanism as the point of operation is transferred about the shoe, which machines for convenience may be termed automatic shoe sewing machines.

The invention is illustrated in the present application as embodied in a machine for sewing outsoles to the welts of welted shoes. The invention, however, is not limited in its application to automatic outsole shoe sewing machines, but certain features thereof may be embodied in other automatic shoe sewing machines.

The present commercial machines for sewing soles to the welts of welted shoes in the operation of which the shoe is held and manipulated by the operator, are provided with welt cutting attachments for operating on the welt along a certain portion thereof during the sewing of a seam. In certain of such attachments the welt cutting knife is constructed and arranged to cut a stitch receiving groove in the welt, while in others the knife is constructed and arranged to bevel off the outer edge of the welt. In the operation of such attachments the welt cutting knife is held out of operation when the machine is sewing along the shank of the shoe on the side of the shoe upon which the seam is started, is thrown into operation when the forepart of the shoe is reached, and is thrown out of operation when the machine arrives at the shank upon the side of the shoe last sewn. The welt cutting knife is arranged to be actuated from a hand lever so that the knife may be thrown into and out of operation by the operator at any point in the sewing of a seam by a suitable movement of the hand lever. Such attachments are impractical in an automatic sewing machine, since the attention of the operator is required during the sewing of a shoe in order to actuate the hand lever to throw the knife into and out of operation at the proper points in the formation of the seam.

One object of the present invention is to produce an automatic shoe sewing machine having a work engaging knife in which the action of the knife is controlled without attention on the part of the operator during the operation of the machine.

Another object of the invention is to provide automatic outsole sewing machines with welt cutting mechanism which will operate upon certain predetermined portions of the welt and leave other portions of the welt uncut without requiring the attention of the operator.

With these and other objects in view, the invention consists in the novel and improved features hereinafter described and particularly pointed out in the claims.

While the invention is particularly advantageous in its application to automatic sewing machines, certain features thereof may be applied to machines in which the shoe is held and manipulated by the operator, and it is to be understood that except as defined in the claims the invention is not limited to any particular machine or type of machine, or to any particular construction or combination.

The invention will be readily understood from the accompanying drawings illustrating the invention in its preferred form, and the following detailed description of the constructions therein shown.

In the drawings Figure 1 is a view, in front elevation, of a machine embodying the invention; Fig. 2 is a view, in side elevation, of the machine looking from the right-hand side thereof; Fig. 3 is a plan view of the machine; Fig. 4 is a detail view, in front elevation, illustrating particularly the edge gage and welt cutting mechanisms; Fig. 5 is a view, in side elevation, of the parts illustrated in Fig. 4; and Fig. 6 is a detail view, in side elevation, illustrating certain parts of the sewing and welt cutting mechanism.

The machine illustrated in the drawings, with the exception of the welt cutting mechanism, has substantially the same construction, arrangement and mode of operation of parts as the machine illustrated and described in applicant's pending application Serial No. 160,751, filed April 9th, 1917.

The sewing mechanism of the illustrated machine comprises a curved hook needle 2, a curved awl 4, a shuttle 6, a tension wheel 8, and certain other devices cooperating with 5 these parts to form a lockstitch seam. The machine is also provided with a work support 10 and a presser-foot 12 arranged to engage opposite sides of the work. The operating parts of the sewing mechanism are 10 driven from a series of cams mounted upon a cam shaft 14.

The lasted shoe is supported during the sewing operation by a jack 16 mounted on the upper end of a spindle 18 supported at its 15 lower end. The supporting devices for the spindle are arranged to permit lateral turning movements and longitudinal and lateral tipping movements to be imparted to the jack to maintain the shoe in the proper position 20 with relation to the stitch-forming mechanism as the point of operation is transferred about the shoe. During the sewing operation the shoe is held at all times at the point of operation by the needle or awl or by the 25 work support and presser-foot so that the tipping and turning movements imparted to the jack will tip and turn the shoe about the point of operation. The jack spindle is supported yieldingly in a vertical direction so 30 that the jack and the shoe carried thereby can move vertically to some extent during the sewing of a seam. The lower end of the spindle is rotatably mounted in bearings in the spindle supporting devices and lateral 35 turning movements are imparted to the jack by turning the spindle. The spindle supporting devices are constructed and arranged to permit the lower end of the spindle to be moved freely in any direction in a 40 horizontal plane, and to allow the spindle to tilt in any direction about a point at or adjacent its lower end, and the tipping movements are imparted to the jack by moving the lower end of the spindle in horizontal 45 directions.

The supporting devices for the spindle comprise a frame 20 supported at the forward end of an arm 22 pivoted to swing vertically on a yoke 24. The yoke 24 in turn 50 is pivotally supported to swing horizontally on a link frame 25 carried by and connecting the swinging arms 26 and 28. The forward end of the arm 22 is held up yieldingly by devices acted upon by a coiled spring 30.

55 The lower end of the spindle is moved forwardly and rearwardly and laterally in opposite directions to tip the jack, and the spindle is rotated to turn the jack to position the shoe with relation to the sewing mechanism as the point of operation is transferred about the shoe through suitable connections from a series of cams mounted on a pattern cam shaft 32.

60 Forward and rearward movements are imparted to the lower end of the jack spindle

65 by means of a cam roll mounted on the arm 28 and arranged to engage a cam on the cam shaft 32. The connections for moving the lower end of the spindle laterally from the cam on the cam shaft 32 employed when a 70 right shoe is being sewn comprise a rod 34, a lever 36, and a cam lever 38. The connections for moving the lower end of the spindle laterally when a left shoe is being sewn, 75 comprise a rod 40, a lever 42, a link 44, a lever 46, and the cam lever 38.

80 The mechanism for rotating the jack spindle comprises a pivoted gear segment 48 meshing with a gear mounted on the spindle. The connections for swinging the gear segment from the cam on the cam shaft 32 employed when a right shoe is being sewn comprise a rod 50, a bell crank 52, a link 54, a pivoted link 56, a link 58, a lever 60, and a cam lever 62. The connections for swinging the gear segment 48 employed when a left shoe is being sewn comprise a rod 64, a bell crank 66, a link 68, a bell crank 70, a 85 link 72, a lever 74, and the cam lever 62.

90 The jack spindle intermediate its lower end and the jack is acted upon by cables 75 and 76 attached at their forward ends to the disk 77 mounted on the spindle and respectively connected at their other ends with the coiled springs 78 and 79. Through the action of the coiled springs the cables tend to swing the jack rearwardly about the lower end thereof so as to keep the projecting edge of the sole of the shoe in proper position between the work support and presser-foot of 95 the machine. The tension of the springs 78 and 79 is controlled so as to cause the springs to exert a comparatively heavy total tension when the machine is operating along certain parts of a shoe, and to exert a comparatively light total tension at other points. These springs through the cables 75 and 76 tend to turn the jack spindle in opposite directions, and their respective tensions are also controlled during the sewing operation so 100 that there is a resultant tendency to turn the jack spindle in a direction opposite that in which it is being turned by the mechanism for rotating the same, above described, thereby eliminating lost motion or back lash in 105 the parts of this mechanism.

110 The driving mechanism for the machine comprises a main driving shaft 80 connected by suitable gearing with the shaft 82, through which both the sewing cam shaft 14 120 and the pattern cam shaft 32 are driven.

125 During the sewing operation the pattern cam shaft 32 is driven from the shaft 82 through mechanism constructed and arranged to drive the pattern cam shaft at variable speed. When a shoe is placed in the machine in position to start the sewing operation, this mechanism is adjusted to drive the cam shaft at the proper speed for the size of the shoe to be sewn through cer- 130

tain connections from the jack. The pattern cam shaft is timed for a predetermined relative rate of feed of the shoe. During the sewing of a seam the sewing cam shaft is 5 driven at a substantially constant speed and the pattern cam shaft is driven at a speed which is constant as long as the shoe is fed at the predetermined rate for which the cam shaft is timed, but is variable to restore the 10 shoe and the cam shaft to their proper time relations when the rate of feed of the shoe varies from this predetermined rate, thereby rendering the shoe out of time with the shaft. The mechanism for producing variations 15 in the speed of the pattern cam shaft to restore the shaft to its proper time relation to the shoe when the shoe is out of time therewith, is also controlled through connections from the jack.

20 The connections for driving the pattern cam shaft from the shaft 82 comprise a cam lever 83 operated from the sewing cam shaft, a bevel gear 84 driven from the cam lever 83 at variable speeds through a pawl and 25 ratchet mechanism, a bevel gear 85, a bevel gear 86, and a spiral gear 88 meshing with a spiral gear 90 secured to the pattern cam shaft. The spiral gear 88 is arranged to be clutched alternatively to the bevel gear 84 30 or to the bevel gear 86 to drive the pattern cam shaft in one direction in sewing a right shoe, and in the opposite direction in sewing a left shoe.

The speed at which the bevel gear 84 is 35 driven may be adjusted to adjust the speed of the pattern cam shaft for the size of the shoe to be sewn, by means of a lever 94 which controls the mechanism for driving the bevel gear through a link 96. Variations 40 in the angular position of the lever 94 will produce variations in the speed of the bevel gear. The lever is adjusted angularly for the size of the shoe to be sewn, as the shoe is placed in operating position in the machine 45 through suitable connections from the jack. During the sewing operation the lever is locked in position.

The speed at which the bevel gear 84 is 50 driven may be varied to vary the speed of the pattern cam shaft during the sewing operation to restore the shoe and the cam shaft to their proper operating positions when the shoe is out of time with the cam shaft, by means of a rod 98, variations in 55 the longitudinal position of which will produce variations in the speed of the bevel gear. The longitudinal position of the rod 98 also is automatically controlled during the sewing operation through suitable connections from the jack.

The connections for adjusting the lever 94 60 to adjust the speed of the pattern cam shaft for the size of the shoe to be sewn, and for controlling the longitudinal position of the rod 98 to control the speed of the cam shaft

during the sewing operation from the jack comprise a lever 100 pivoted on a swinging carrier 102 and connected at its forward end by a bar 104 with the forward end of the jack, and at its rear end with the left-hand 70 end of the rod 98, and a lever 106 mounted on a hanger 108 and pivotally connected at its forward end with the lever 100. The hanger 108 is pivoted at 110 to the lever 94. This pivotal connection 110 forms a virtual 75 or effective pivot for the lever 106. The lever 106 is swung about its pivot 110 in timed relation to the rotation of the pattern cam shaft through certain connections from a cam mounted on the shaft 32. The connections for moving the lever from the cam on the cam shaft employed when a right shoe 80 is being sewn comprise a lever 112, a link 113, a lever 114, and a cam lever 115. The connections employed for moving the lever 106 from the cam on the cam shaft when a left shoe is being sewn comprise the lever 112, a link 116, a lever 117, and the cam lever 115.

When the machine is at rest with the 90 parts in condition for the placing of a shoe in position in the machine, the rod 98 is locked against longitudinal movement and the lever 94 is free to swing about its axis. By the placing of the shoe in operating position in the machine, the lever 94 is adjusted angularly through the connections between the lever and the jack in a position depending upon the size of the shoe placed in the machine. The adjustment of the lever 100 determines the position of the pivot 110 of the lever 106, and also through the link 96 regulates the speed of the pattern cam shaft for the size of the shoe to be sewn. During the sewing operation the lever 94 is 105 locked in position while the rod 98 is then unlocked so that it is free to move longitudinally. When the shoe is fed at the predetermined rate relative to the speed of the pattern cam shaft, the rod 98, through its 110 connections with the jack, will be maintained in a constant longitudinal position. Upon the occurrence of a variation in the rate of feed of the shoe from the predetermined 115 rate, the rod 98 will be moved longitudinally to produce a variation in the speed of the cam shaft to restore the shoe and the cam shaft to their proper time relations.

The sewing mechanism, the mechanism 120 for supporting the jack, the mechanism for imparting turning and tipping movements to the jack to present the shoe properly to the sewing mechanism, the mechanism acting yieldingly on the jack spindle to maintain the projecting edge of the shoe in position between the work support and the presser-foot and to eliminate backlash in the parts of the jack actuating mechanism, the mechanism for adjusting the speed of the pattern cam shaft for the size of the shoe 125 130

to be sewn, and the mechanism for varying the speed of the pattern cam shaft during the sewing of a seam to restore the shoe and the cam shaft to their proper time relations 5 described above, have the same construction, arrangement and mode of operation as the corresponding mechanisms of the machine illustrated and described in applicant's application Serial No. 160,751, and reference 10 may be had to this application for a full and complete description of the same.

The machine is provided with a movable work gage for determining the position of the seam relative to the edge of the sole. 15 This gage in the machine illustrated is arranged to engage the edge of the sole of the shoe. When sewing along the shank of a shoe on the side thereof on which the seam is started, the gage is retracted out of position to engage the sole, and the position of the seam is then determined by the engagement of the upper with the front side of the work support, the seam then being located relatively remote from the sole edge and 20 close to the upper. When the forepart of the shoe is reached the gage is moved forward into engagement with the sole edge and locates the seam relatively close to the edge of the sole. Upon reaching the shank 25 of the shoe upon the opposite side thereof, the gage is retracted, allowing the seam again to be located relatively remote from the sole edge by the engagement of the forward side of the work support with the upper 30 per.

The work gage is indicated in the drawings at 118, and consists of a suitably-shaped arm mounted on the upper end of a shaft 120 to swing over the upper surface of 40 the work support 10. The shaft 120 is mounted to turn in suitable bearings in the upright 122 formed on the feed slide 124. Upon the lower end of the shaft 120 are formed a series of spiral gear teeth 126 45 meshing with the teeth of a spiral gear 128 mounted on the inner end of a horizontal shaft 130 journaled in bearings in the feed slide. To the outer end of the shaft 130 is secured a disk 132 formed with a gear segment 134, the teeth of which mesh with the teeth of a gear segment 136 carried at the upper end of an arm 138 secured to one end of the shaft 140 mounted in bearings in the bracket 142. To the opposite end of the 50 shaft 140 is secured an arm 144 carrying a roll 146 engaging the end of an arm 148 secured to a shaft 150. To this shaft is secured a second arm 152 carrying a cam roll arranged to engage a peripheral cam on a 55 cam disk attached to the pattern cam shaft 32. A tension spring 154 acting on the arm 138 tends to swing the same rearwardly and maintains the cam roll on the arm 152 in engagement with the periphery of the cam disk. Through the mechanism described, 60

the shaft 120 is controlled and actuated to maintain the edge gage in retracted position during the starting of the seam along the shank, to swing the gage forwardly into operating position when the forepart is 70 reached, and to retract the gage out of operating position upon arriving at the shank upon the side of the shoe last sewn.

156 indicates the oscillating cam lever for reciprocating the feed slide, and 158 75 the hand lever connected with the lever 156 by a block 159 mounted on a pin secured in the lever 158 and engaging a groove in the lever 156 for adjusting the length of feed. The hand lever 158 swings over a segment 80 plate 160 having a series of holes in which are placed pins 162 and 164 to limit the movement of the hand lever. To the hand lever 158 is secured a plate 166 having a downturned forward end. The disk 132 is 85 formed with an abutment or shoulder 168 for engagement with the downturned end of the plate 166 to swing the hand lever forwardly to lengthen the feed, and a block 170 formed integral with the disk 132 carries a 90 segmental plate 172 for engagement with the forward end of the plate 166 to swing the hand lever rearwardly to shorten the feed. By this construction, as the disk 132 is 95 rotated to advance the edge gage in passing from the shank of the shoe to the forepart, the hand lever 158 is swung rearwardly to shorten the feed, and as the disk 132 is rotated to swing the edge gage rearwardly in passing from the forepart to the shank, the lever 158 is swung forwardly to lengthen the feed.

As illustrated in the drawing, the machine is provided with a channel-cutting mechanism for cutting a channel in the welt for the reception of the stitches of the seam. The channel cutting knife is indicated at 174 and is mounted on the feed slide with its upper end engaging in a slot in the work support. With the knife mounted on the 110 feed slide the knife executes its cutting stroke during the retracting movement of the slide while the work is held stationary through the engagement of the needle, presser-foot and work support therewith.

The channel cutting knife is mounted on the feed slide for vertical movement so that it may be projected above the upper surface of the work support into position to engage the welt, or withdrawn below the upper surface of the work support out of operating position. When the seam is started along the shank of a shoe the knife is withdrawn out of operating position. Upon arriving at the forepart of the shoe the knife is projected upwardly through the work support into engagement with the welt, and operates to cut a groove or channel in the welt in which the stitches are laid. When the shank 120 of the shoe upon the side of the shoe last 125 130

sewn is reached, the knife is withdrawn out of operating position. The welt is thus channeled by the cutting knife about the forepart of the shoe and is left unchanneled 5 at the shank.

In the construction shown, the knife is formed at the upper end of a knife bar 176. The upper end of the knife bar is arranged to slide in a suitably-shaped opening in a 10 projection 178 on the feed slide which forms a guide for the upper end of the bar. The lower end of the knife bar is formed with an opening in which engages an eccentric sleeve 180 mounted on a pin 182 projecting 15 from a collar or sleeve 184, the sleeve being held in position on the pin by a nut 186. The sleeve 184 is mounted on the shaft 120 and is formed with interior screw threads 20 of steep pitch engaging corresponding screw threads 187 formed on the shaft. The inter-engaging threads on the shaft and sleeve are arranged so that as the shaft is turned to advance the work gage into operative position, the knife bar is elevated to project the 25 knife upwardly above the upper surface of the work support into engagement with the welt, and that as the shaft is turned in the opposite direction to retract the gage the knife bar is depressed to withdraw the 30 knife below the upper surface of the work support.

The position of the knife may be adjusted to regulate the depth of the channel cut by the knife in the welt by adjusting the eccentric sleeve 180. The knife bar is supported by the projection 178 close to the knife during the cutting stroke of the knife, thereby eliminating any danger of bending the 35 knife bar.

Having explained the nature and object 40 of the invention, and having specifically described a machine embodying the invention in its preferred form, what is claimed is:

1. A sewing machine for sewing soles to 45 the welts of welted shoes, having, in combination, stitch forming devices, a shoe supporting jack, mechanism for changing the relative positions of the stitch forming devices and the jack to present the shoe properly to the stitch forming devices as the 50 point of operation is transferred about the shoe, a work-engaging knife, and automatic mechanism for throwing the knife into and out of operation at predetermined points in the 55 formation of a seam.

2. A sewing machine for sewing soles to 60 the welts of welted shoes, having, in combination, stitch forming devices, a shoe supporting jack, mechanism for changing the relative positions of the stitch forming devices and the jack to present the shoe properly to the stitch forming devices as the 65 point of operation is transferred about the shoe, a knife for cutting a stitch receiving

for throwing the knife into and out of operation at predetermined points in the formation of a seam.

3. A sewing machine for sewing soles to 70 the welts of welted shoes, having, in combination, stitch forming devices, a shoe supporting jack, mechanism for changing the relative positions of the stitch forming devices and the jack to present the shoe properly to the stitch forming devices as the 75 point of operation is transferred about the shoe, a movable gage for determining the position of the seam with relation to the edge of the sole, a work engaging knife, and automatic mechanism for shifting the gage 80 and for throwing the knife into and out of operation at predetermined points in the formation of a seam.

4. A sewing machine for sewing soles to 85 the welts of welted shoes, having, in combination, stitch forming devices, work feeding means, mechanism for adjusting the length of feed during the operation of the machine, a shoe supporting jack, mechanism for changing the relative positions of the 90 stitch forming devices and the jack to present the shoe properly to the stitch forming devices as the point of operation is transferred about the shoe, a movable gage for determining the position of the seam 95 with relation to the edge of the sole, a work-engaging knife, and automatic mechanism for shifting the gage, for operating the feed adjusting mechanism to change the feed length, and for throwing the knife into and 100 out of operation at predetermined points in the formation of a seam.

5. A sewing machine for sewing soles to 105 the welts of welted shoes, having, in combination, stitch forming devices, a work engaging knife arranged to remain continuously inactive during the formation of a series of stitches, and automatic mechanism for throwing the knife into and out of operation at predetermined points in the 110 formation of a seam.

6. A sewing machine for sewing soles to 115 the welts of welted shoes, having, in combination, stitch forming devices, work feeding means, mechanism for adjusting the length of feed during the operation of the machine, a movable gage for determining the position of the seam with relation to the edge of the sole, a work engaging knife, and automatic mechanism for shifting the gage, 120 for operating the feed adjusting mechanism to change the feed length, and for throwing the knife into and out of operation at predetermined points in the formation of a seam.

7. A shoe sewing machine having, in combination, stitch forming and work guiding and feeding devices for sewing a seam extending around the periphery of a shoe, a work engaging knife arranged to remain 125

continuously inactive during the formation of a series of stitches, and automatic mechanism for throwing the knife into and out of operation during the continued operation of the stitch forming devices in sewing a seam.

8. A shoe sewing machine having, in combination, stitch forming devices, a shoe supporting jack, mechanism for changing the relative positions of the stitch forming devices and the jack to present the shoe properly to the stitch forming devices as the point of operation is transferred about the shoe, work cutting mechanism arranged to be placed either in an active or in an inactive condition, and automatically actuated and controlled means for shifting said mechanism from one of said conditions to the other at a predetermined point in the formation of a seam.

9. A shoe sewing machine having, in combination, stitch forming devices, a shoe supporting jack, mechanism for changing the relative positions of the stitch forming devices and the jack to present the shoe properly to the stitch forming devices as the point of operation is transferred about the shoe, a work cutting device arranged to remain inactive during the formation of a series of stitches and automatically actuated and controlled mechanism for throwing said cutting device into operation at a predetermined point in a seam formation.

10. A shoe sewing machine having, in combination, stitch forming and work guiding and feeding devices for sewing a seam extending around the periphery of a shoe, a work cutting device arranged to remain inactive during the formation of a series of stitches, and automatically actuated and controlled mechanism for throwing said cutting device into operation during the continued operation of the stitch forming devices in sewing a seam and at a predetermined point in the formation of the seam.

11. A sewing machine for sewing soles to the welts of welted shoes having, in combination, stitch forming devices, a work engaging knife arranged to cut a stitch receiving channel in the work, a movable gage for determining the position of the seam and a cam and suitable connections for moving

the knife into and out of operative position and for moving the gage.

12. A sewing machine for sewing soles to the welts of welted shoes having, in combination, stitch forming devices, a work support for supporting the welt and sole during the sewing operation, a feed slide, a welt channeling knife mounted on the feed slide and arranged to project through a slot in the work support in line with the needle in the direction of feed, and means acting automatically to move the knife into and out of operative position.

13. A sewing machine for sewing soles to the welts of welted shoes having, in combination, stitch forming devices, a work support, a feed slide, a horizontal shaft mounted in the feed slide, a vertical shaft mounted in the feed slide, a work gage at the upper end of the shaft, operating connections between the shafts, means for rocking the horizontal shaft, a work engaging knife, and connections between the knife and the vertical shaft for moving the knife into and out of operative position.

14. A sewing machine for sewing soles to the welts of welted shoes having, in combination, stitch forming devices, a work support on which the welt rests during the sole sewing operation, a feed slide, a knife mounted on the feed slide engaging the work at the point where it is supported by the work support, a work gage mounted on the feed slide arranged to engage the work in proximity to the work support, a shaft mounted on the feed slide, means for rocking the shaft, and connections to the gage and knife for shifting the position of the gage and for moving the knife into and out of operative position.

15. A sewing machine for sewing soles to the welts of welted shoes having, in combination, stitch forming devices, a work support, a horizontal shaft mounted below the work support, a vertical shaft, a work gage at the upper end of the shaft, operating connections between the shafts, means for rocking the horizontal shaft, a work engaging knife, and connections between the knife and the vertical shaft for moving the knife into and out of operative position.

LAURENCE E. TOPHAM.
